UNITED STATES PATENT OFFICE.

ARTHUR DOUGLAS KENYON, OF DENVER, COLORADO, ASSIGNOR TO GENERAL MACHINERY & SUPPLY COMPANY, OF DENVER, COLORADO.

ELECTRIC DRILL OR HAMMER.

Application filed January 14, 1922. Serial No. 529,395.

To all whom it may concern:

Be it known that I, ARTHUR D. KENYON, a citizen of the United States, residing at Denver, in the county of Denver and State of Colorado, have invented a new and useful Electric Drill or Hammer, of which the following is a specification.

The device forming the subject matter of this invention is a hammer or drill, the reciprocating core of which moves responsive to solenoid magnets, and the invention aims to provide novel means for energizing and deenergizing the solenoid magnets automatically, through the instrumentality of the reciprocating core. Another object of the invention is to provide novel means whereby the operation of the tool may be stopped and started at will.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in longitudinal section, a device constructed in accordance with the invention, parts being broken away; Figure 2 is a section on the line 2-2 of Figure 1; Figure 3 is an end elevation.

In carrying out the invention there is provided a frame 1 including a head 2 carrying a handle 3. A tubular body 4 is connected by threading or otherwise, as indicated at 5, with the head 2, and includes an end wall 6 having a boss 7. An inner tubular guide 8 is bound between the boss 7 and the head 2, the boss and the head having recesses 9 for the reception of the ends of the guide 8. The numeral 10 marks an outer guide which is threaded as indicated at 11, upon, or secured otherwise to, the boss 7. The guide 10 and the boss 7 have shoulders 12. A tappet 14 is mounted for reciprocation in the guide 10 and has a head 15 adapted to cooperate with

the shoulders 12 to limit the movement of the tappet.

An outer solenoid 16 is located in the body 4, about the inner guide 8 and is located adjacent to the end wall 6. An inner solenoid 17 is disposed within the body 4 about the guide 8, and is located adjacent to the head 2. The device includes a core adapted to move responsive to the solenoids 16 and 17. The core comprises a body 18, slidable in the guide 8, and a reduced stem 19, passing through an opening 29 in the part 2, the stem having a head 20 at its outer end.

Ears 21 project inwardly from one side portion of the handle 3. The numeral 22 marks a switch member provided at its ends with projections 23 and 230. The switch member has a flange 24, received between the ears 21, and connected thereto by a pivot element 25. A contact 26 is mounted on one end of the switch member 22 and is insulated therefrom. The contact 26 is adapted to cooperate with a contact 27 carried by a spring tongue 28, secured to one of the ears 21 and insulated therefrom.

A slot 30 is formed in the handle 3, one end of a link 31 extending into the slot, the said end of the link being carried by a pivot element 32 mounted in the handle 3. A lever 33 extends through the slot 30 and is fulcrumed intermediate its ends on a pivot element 34 mounted in the handle 3. The numeral 35 designates a connection, preferably in the form of a bar, the ends of the connection 35 being pivoted at 36 to the inner ends of the lever 33 and the link 31. A switch member 37 is provided, and is equipped with projections 38 and 39. The switch member 37 has a flange 40, pivoted at 41 to the connection 35. A contact 42 is mounted on one end of the switch member 37 and is insulated therefrom, the said contact being adapted to cooperate with a contact 43 carried by a spring tongue 44 mounted on a finger 45 projecting inwardly from one side portion of the handle 3, the spring tongue being insulated from the finger.

A bore 46 is fashioned in the handle 3, and in the bore, an operating member, such as a plunger 47 is mounted for reciprocation. The outer end of the lever 33 is provided with a seat 48 wherewith the inner

end of the plunger 47 cooperates. A slot 49 is formed in the handle 3, the plunger 47 having a pin 50, mounted to move in the slot, these elements cooperating to limit the 8 sliding movement of the plunger 47. At its outer end, the plunger 47 carries a head 51. A compression spring 52 surrounds a portion 10 of the plunger 47 and is interposed between the head 51 on the plunger and an abutment 53 on the handle 3.

The tubular body 4 carries a binding post 54. One end 55 of the winding of the outer solenoid 16 is connected to the binding post 54. One end 56 of the winding of the inner solenoid 17 is connected to the binding post 54. A conductor 57 is likewise connected to the binding post 54. The other end 58 of the winding of the solenoid 16 is connected to the contact 42 on the pivotally mounted switch member 37. The corresponding end 63 of the winding of the solenoid 17 is connected to the contact 27 on the spring tongue 28. A conductor 61 connects the contact 26 on the pivotally mounted switch member 22 with a binding post 60 on the head 2. A conductor 59 connects the binding post 60 with the contact 43 on the spring tongue 44. A conductor 62 is connected to the binding post 60.

30 For convenience in setting forth the operation of the tool let two circuits be traced out at this point, these circuits being designated as circuit A and circuit B.

Circuit A includes a conductor 62, the 35 post 60, the conductor 59, the contact 43, the contact 42, the end 58 of the winding of the solenoid 16, the winding of the solenoid 16, the end 55 of the winding of the solenoid 16, the binding post 54, and the conductor 57.

40 Circuit B includes the conductor 62, the post 60, the conductor 61, the contact 26, the contact 27, the end 63 of the winding of the solenoid 17, the winding of the solenoid 17, the end 56 of the winding of the solenoid 17, the post 54, and the conductor 57.

45 For convenience, let it be supposed that the tool is held vertically, reference being had to Figure 1, the terms upwardly and downwardly and the like, being selected accordingly.

50 Referring to Figure 1, the core 18-19 may be considered to have moved upwardly, responsive to the solenoid 17. When the core has arrived in the position shown in 55 Figure 1, the head 20 on the stem 19 of the core engages the projection 23 on the switch member 22, the switch member 22 being tilted on its fulcrum 25, the contact 26 being spaced from the contact 27, circuit B being 60 open, and the solenoid 17 being deenergized. The head 20 on the stem 19 engages the projection 28 on the switch member 37, the switch member 37 tilting on its fulcrum 41, and the contact 42 being closed on the contact 43. Circuit A now is closed, and the

solenoid 16 is energized, whereupon the core 18-19 will move downwardly.

When the core 19 moves downwardly, the head 20 engages the projection 230 on the switch member 22, the switch member 22 70 tilts on its fulcrum 25, the contact 26 is brought into engagement with the contact 27, and the solenoid 17 is energized, at the time that the core 18-19 arrives at the limit of its downward stroke. Simultaneously, 75 the head 20 engages the projection 39 on the switch member 37, tilting the switch member on its fulcrum 41, the contact 42 being spaced from the contact 43, and the solenoid 16 being deenergized. The core 80 then moves upwardly, responsive to the action of the solenoid 17.

As is well understood in the art, the body portion 18 of the core coacts with the tapet 14 to impart reciprocation thereto.

When the plunger 47 is thrust downwardly, as shown in Figure 1, the lever 33 and the link 31 are tilted, and the connection 40 carries the switch member 37 inwardly, so that its projections 38 and 39 lie 90 in the path of the head 20 on the core. When, however, pressure on the head 51 of the plunger 47 is released, the spring 52 reacts, withdrawing the plunger 47, and permitting the lever 33 and the link 31 95 to drop downwardly, the switch member 37 thus being disposed in such a position that its projections 38 and 39 are out of the path of the head 20. The operator, in view of the foregoing, has within his control a 100 means whereby the operation of the tool may be stopped at will.

What is claimed is:

1. In a tool of the class described, a frame; solenoids carried thereby; a core 105 movable in opposite directions responsive to the solenoids; tilttable switch members supported on the frame and interposed in the circuits of the solenoids, the switch members being located in the path of the 110 core, to be operated thereby, and means under the control of the operator for raising one switch member to operative position.

2. In a tool of the class described, a frame; solenoids carried thereby; a core 115 movable in opposite directions responsive to the solenoids; tilttable switch members supported on the frame and interposed in the circuits of the solenoids, the switch members being engageable by the core to be operated thereby; means under the control of an operator for moving one switch member into the path traversed by the core.

3. In a tool of the class described, a frame; solenoids carried thereby; a core 125 movable in opposite directions responsive to the solenoids; switch members pivotally supported on the frame intermediate their ends, each switch member being provided at both ends with projections located in the 130

path traversed by the core, the switch members being provided at opposite ends with means for opening and closing the circuits of the respective solenoids.

- 6 4. In a tool of the class described, a frame; solenoids carried thereby; a core movable in opposite directions responsive to the solenoids; a tiltable switch member supported immediately on the frame and including parts located in the path traversed by the core; a second switch member including parts located in the path traversed by the core, the switch members being interposed in the circuits of the solenoids; a

lever fulcrumed on the frame; means for mounting the second switch member for pivotal movement on the lever, the lever constituting means for moving the switch member into the path traversed by the core; and means under the control of an operator for actuating the lever.

In testimony that I claim the foregoing as my own, I have hereto affixed my signature in the presence of two witnesses.

ARTHUR DOUGLAS KENYON.
